UNITED STATES PATENT OFFICE.

ARDEN S. FITCH, OF NEW YORK, N. Y.

CANOPY-HOLDER FOR CHILDREN'S CARRIAGES.

SPECIFICATION forming part of Letters Patent No. 294,376, dated March 4, 1884.

Application filed August 2, 1883. (No model.)

To all whom it may concern:

Be it known that I, ARDEN S. FITCH, of the city, county, and State of New York, and a citizen of the United States, have invented an Improved Canopy-Holder for Children's Carriages, of which the following is a full, clear, and exact description, reference being had to the accompanying drawings, forming part of this specification.

10 My invention consists in the hereinafter-described devices for holding the canopy of a child's carriage, and permitting the adjustment of the canopy in either a horizontal position or inclined rearwardly or forwardly, 15 or from side to side, as and for the purpose set forth.

Figure 1 is a side elevation of a canopy and supporting-rod, and showing my improved holding device. Fig. 2 is an enlarged side 20 elevation of my improved device, showing the same on the end of the supporting-rod. Fig. 3 is a vertical sectional view of my device, as shown in Fig. 2. Fig. 4 is a plan of my device as it appears in the first stage of its manufacture; and Fig. 5 is a side elevation of the button on the end of the canopy-ferrule, which I preferably employ in connection with my holder.

My holding device consists of the metallic 30 leaf-spring A, preferably of steel, which is formed with the loop a about midway of its ends, adapted to be clasped or gripped upon the supporting-rod B, and with the ends a' extending from the side of said loop, substantially parallel to each other, and adapted to have seated between their inner faces and to there hold a button on the extremity of the canopy-ferrule, as shown.

In fabricating my spring-holder it is preferably struck by a die from a suitable blank 40 cut from a sheet of metal into the form shown in Fig. 4; and it is desirable that this blank should be narrowed toward its opposite ends, as shown in the drawings, so that the ends 45 which receive between them the ferrule-button should be of less force or resiliency as springs than the central portion of the blank forming the loop a, which grips the rod B. It is also desirable that the inner and adjacent faces of 50 the ends a' should be concaved, as shown at a², so that they will fit upon a button, which is

convex on each side, as shown; and, furthermore, it is preferable that the bearing or gripping face of one of the ends a' should have the radial groove a³ across it, as shown, adapted 55 to receive the tooth or diametrical projection c on the corresponding face of the ferrule-button. The parallel ends a' of the spring are also preferably bowed out, as shown at a⁴, about midway between the loop a and the 60 bearing-faces of said ends, so that the independence of the resiliency or spring action of the ends a' from the spring action of the loop a is increased.

The blank shown at Fig. 4, and thus formed, 65 may be struck at one operation from a metal sheet by a suitable die. To form the loop a, the blank is then bent upon itself on a suitable mandrel, or in another die, so that the loop a is in the form of a cylindrical sleeve, and preferably with its interior diameter somewhat less than the diameter of rod B. By this means, when it is slipped upon the rod by suitably spreading the said loop a, it will close down 70 upon and firmly grip the rod with sufficient 75 force to hold the device in any desired position on the rod—that is, with the ends a' vertically pendant from the rod or extended at either side from the rod—and at the same time will permit the holder to be moved easily 80 around the rod into these desired positions.

The ferrule C of the canopy has the button c, preferably convex on its opposite faces, as at c', and also preferably with the tooth or projection c² across one of said faces. A pin, 85 c³, transverse of the shank c⁴ of the button, is desirably provided. Now, when the button is seated, as shown, between the ends a' of the leaf-spring A, it will, with the canopy, be held thereby in any desired position over the carriage, either horizontal or inclined to front or rear, and the spring will be assisted by the tooth or rib c² meshing in the radial serrations a². The canopy may be swung and held inclined from side to side over the carriage by 95 swinging the loop a more or less around the rod B. If it is desired to have the loop a traverse the rod B lengthwise, the loop a may be loosened by means of twisting the button c by the cross-rod c³ in its seat sufficiently to 100 overcome the spring of said loop.

It is evident that the button c may be readily

seated and unseated between the ends a' of the holder, and thus the canopy removed or replaced at pleasure.

The advantage gained by my holder is that 5 the canopy may be instantly adjusted in any desired position by simply grasping the ferrule and turning or bringing the canopy into the desired attitude, when it will be held by the spring-holder A.

10 What I claim as my invention, and desire to secure by Letters Patent, is—

1. The combination, with the supporting-rod B, of the leaf-spring holder A, having the loop a to grip the rod, and the parallel ends 15 a' , with the button c on the canopy-ferrule C, adapted to be gripped by said ends a' , as and for the purpose specified.

2. The combination, with the supporting-rod B, of the leaf-spring holder A, the wide 20 middle portion of which forms the rod-gripping loop a , and the narrowed ends of which are parallel to each other and form a grip for the button c on the canopy-ferrule C, substantially as and for the purpose set forth.

3. The combination, with the supporting-rod B, of the leaf-spring holder A, having the rod-gripping loop a , and the ends a' , recessed at a' , together with the ferrule C, having button c , with convex opposite sides c' , as and for the purpose specified. 25

4. The combination, with the supporting-rod B, of the leaf-spring holder A, having the rod-gripping loop a and extended parallel ends a' , on the bearing-face of one of which are the radial depressions a^3 , together with the ferrule-button c , having the rib c^2 across one side, and arranged to operate as and for the purpose described. 30

5. The combination, with the rod B, of the leaf-spring holder A, having the loop a and 40 the extended parallel ends a' , together with the ferrule C, having the shank c^4 , carrying the button c and the pin c^3 , all arranged to operate as and for the purpose specified.
